CLAIM

The ornamental design for a floating chair, as shown and described.

DESCRIPTION

FIG. 1 is a perspective view of a floating chair, showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top plan view thereof; and,

FIG. 7 is a bottom plan view thereof.

The broken lines shown in the figures are for purposes of illustrating portions of the floating chair and form no part of the claimed design.
